GRINDER

Harry J. Criner, Davenport, Iowa, assignor of
one-half to A. G. Bush, Davenport, Iowa

Application July 29, 1937, Serial No. 156,331

7 Claims. (Cl. 51—32)

My invention relates to improvements in grinders for slicing blades, such as the scalloped blades commonly used in bread slicing machines.

The objects of my invention are to provide an economical, efficient grinding machine by which the slicing blades of a bread slicer may be ground without removing the blades from the reciprocating frame commonly used to support and drive the blades during the cutting operation; also, to afford means for successively grinding a plurality of blades mounted in a suitable retaining frame or for grinding a single blade so held.

My apparatus is designed primarily for sharpening used blades rather than for the original grinding of blades, although it is obvious that it may be adapted for the original grinding of blades if desired.

I attain these objects by the means illustrated in the accompanying drawings, in which,—

Figure 1 is a vertical section of my machine on the line 1—1 of Figure 2;

Figure 2 is a plan view of my machine;

Figure 3 is a cross-section on the line 3—3 of Figure 1;

Figure 4 is an enlarged sectional detail on the line 4—4 of Figure 1;

Figure 5 is an enlarged detail elevation of an alternate form of my machine in which the grinder shaft and motor shaft are integral;

Figure 6 is a plan view of the form shown in Figure 5.

In Figures 2 and 4, I have shown a portion of a rectangular head frame, 40, such as is commonly used in slicing machines, but for clearness I have omitted this head frame in Figure 1.

Similar numerals refer to similar parts throughout the several views.

My apparatus comprises a support, 11, which is preferably a round shaft or column having a 40 sliding foot, 12, united to the lower end thereof by a pin, 12', adapted to rest upon a table or counter, 13, or other suitable base. The foot, 12, may be a small circular foot, as shown at 12 in Figure 1, or it may have an extended base, 12'', united thereto as shown in Figures 5 and 6.

Upon the support, 11, I mount a sleeve, 8, which is slidable upon the support, 11, and may be secured in place by a thumb screw, 10, at any height necessary to correspond to the height of the various blades on a given set of blades, 24, secured in the head frame, 40.

To the inner side of the sleeve, 8, may be united a bracket or arm, 9, carrying a hub, 7, in which one end of a laterally extending shaft, 17, is

rigidly secured by a set screw, 1', or other suitable means.

Upon the opposite end of the shaft, 17, I mount a square head, 20, rigidly secured to the shaft, 17, by a pin or bolt, 22. In the upper and lower 5 faces of the head, 20, I cut slots in which keys, 21 and 21', are rigidly secured.

Intermediate the hub, 7, and the head, 20, I mount slidingly upon the shaft, 17, a sleeve, 14, having a collar, 14', formed integral with one end 10 thereof. This sleeve, 14, is tubular, but may be eccentric to the shaft, 17, so that by rotating either the sleeve, 14, or the shaft, 17, the height 15 of the bearings mounted upon the sleeve, 14, may be varied.

I prefer to mount the shaft, 17, in the hub, 7, with a set screw, 1', in such manner that the set screw may be loosened and the shaft, 17, rotated to any desired angle. The set screw, 1', may be then tightened and the shaft rigidly secured in 20 its rotated position.

In the shaft, 17, I cut a longitudinal slot, 15, into which the inner end of a set screw, 16, projects, the set screw being threaded in the sleeve, 14. The slot, 15, is made somewhat wider than 25 the diameter of the set screw, 16, as shown in Figure 2, so as to permit a limited rotational movement thereof, the extent of such rotational movement depending upon the width of the slot, 15, and the relative diameter of the pin or set 30 screw, 16.

Upon the sleeve, 14, I mount at either end, bearings, 2 and 3. The bearing, 2, is preferably secured to the sleeve, 14, by a set screw, 2'. The bearing, 3, has secured in the upper face thereof 35 a handle, 6, which may be formed integral with the bearing, 3, or suitably united thereto.

Extending downwardly from the bearings, 2 and 3, I form integral with the bearings, arms, 4 and 5, which carry a cylinder, 1, or a motor housing, 40 1'', in which a shaft, 33, is mounted upon ball-bearings, 38 and 38'. This shaft, 33, may be driven by a drive shaft, 34, suitably connected to the rear end thereof, or it may form a motor shaft for the motor, 1'. 45

The shaft, 33, extends forwardly and has its forward end threaded at 31 to mesh with threads, 30, formed upon a bushing upon which the grinder head, 29, is rigidly mounted. Dust plates, 39 and 39', may be secured in opposite ends of 50 the housing, 1, if desired. The grinder head, 29, is made in cylindrical form with a diameter small enough to permit it to pass between adjacent blades in the slicer frame, which ordinarily are from three-quarters of an inch to an inch apart, 55

according to present practice, but the size and proportions of the grinding head, 29, may be varied to suit the requirements of different cases. The grinding head, 29, is preferably made of carbide, but may be formed of any suitable abrasive material desired.

The drive shaft, 34, may be driven by an individual motor mounted thereon or by any other desired means permitting the necessary flexibility.

10 A rectangular head frame, 18, is formed with parallel rearwardly projecting flanges, 18' and 18'', which have parallel slots, 19, cut in them into which the keys, 21 and 21', may enter.

15 The outer ends of the frame, 18, are extended downwardly and forwardly and formed integral with a supporting plate, 25, leaving an opening, 28, through which the grinding head, 29, may pass and operate. The supporting plate, 25, extends the full length of the frame, 18, and has a clamping plate, 26, united thereto by thumb screws, 27, or other suitable means.

20 In the operation of my machine the supporting plate, 25, and clamping plate, 26, are rigidly secured to one of the blades, 24, which are to be sharpened, the blades, 24, being held securely in a blade frame, 40, which may be the usual type of removable blade frame in common use in bread slicing machines, or a special frame in which the blades may be mounted merely for 30 the purpose of being ground.

The frame, 40, will preferably rest upon the same table or counter as the grinding apparatus, but may be supported in juxtaposition thereto in any desired manner.

35 The grinding apparatus will then be moved into position so that the keys, 21 and 21', are in their proper position in opposed slots, 19. These slots are made of sufficient length to insure the shaft, 17, standing at right angles to the head frame, 18, and to the blades, 24.

40 The sleeve, 14, is then slid forward on the shaft, 17, so as to bring the grinder into contact with one of the scallops of the cutting blade. The handle, 6, is then swung from side to side, thereby swinging the grinder through an arc 45 equal to the length of one scallop on the blade, and a grinding head may be simultaneously caused to travel longitudinally so as to present successive portions thereof in contact with the blade. It will be understood that the blades 50 are mounted upon the supporting bar, 25, in such position that the middle of each scallop is directly in line with the middle of its corresponding slots, 19, and the length of the arms, 4 and 5, and the height of the shaft, 32, in the cylinder, 1, is so regulated that this arc will correspond to 55 the ground faces of the scallops.

In re-sharpening blades, it will be understood that only a very small portion of the metal is to 60 be taken off—ordinarily one-thousandth of an inch is ample for this purpose and the grinding heads shown will sharpen a large number of blades without appreciable wear, but when worn, may be thrown away and replaced with new, as they are very inexpensive.

65 While I have shown the sleeve, 8, securable in position by a set screw, 10, it is obvious that any desired form of adjustment may be utilized to regulate the height of the shaft, 17.

70 It is also obvious that as the adjustment of the eccentric sleeve, 14, varies the relative position of the cylinder, 1, and the arc of travel of the grinding head, 29, the relative position of the supporting plate, 25, upon the blade, 24, may 75 be varied so as to secure the proper alignment

of the grinding head and the scallops of the blades.

I have shown a readily applied clamp to secure the blades and the head frame, but in the case of steel cutting blades, the supporting bar, 25, may be of steel or iron and magnetized so as to hold the blades firmly by magnetic attraction while being ground, or any other desired form of attachment may be used.

I do not limit my claims to the precise forms 10 of parts shown in the drawings, because it is obvious many modifications thereof may be made without departing from the spirit of my invention.

I claim:

1. A grinding machine for sharpening scalloped blades, comprising a base, a supporting column secured thereto, a sleeve adjustably mounted upon the column supporting a transverse shaft and rigidly united thereto, a sleeve slidably mounted upon the shaft and rotatable thereon, a shaft housing parallel with and carried by the sleeve and spaced therefrom, a grinder shaft revolvably mounted in the housing and carrying a cylindrical grinding head mounted thereon extending forwardly from the housing, and means to secure a scalloped slicing blade in juxtaposition to the grinding head.

2. A grinding machine for sharpening scalloped blades, comprising a base, a supporting column secured thereto, a sleeve adjustably mounted upon the column supporting a transverse bar and rigidly united thereto, a block united to the free end of the bar carrying a key rigidly secured therein, a sleeve slidably mounted upon the 35 shaft and rotatable thereon, a shaft housing parallel with the sleeve and spaced therefrom, a grinder shaft revolvably mounted in the housing and carrying a cylindrical grinding head mounted thereon extending forwardly from the 40 housing in combination with a head frame having successive slots formed therein adapted to receive the key, and means to secure the head frame in fixed spaced position relative to blade to be sharpened.

3. A grinding machine for sharpening scalloped blades, comprising a base, a supporting column secured thereto, a sleeve adjustably mounted upon the column supporting a transverse bar and rigidly united thereto, an eccentric sleeve 50 slidably mounted upon the bar and rotatable thereon, a shaft mounted parallel with and carried by the sleeve and spaced therefrom adapted to swing through a limited arc of travel corresponding to the arc of the blade scallops, a small diameter elongated cylindrical grinding head mounted on a forwardly extending end of said shaft, means to secure a slicing blade with its scallops in successive juxtaposition to the grinding head, and contacting lightly therewith, and 60 means to secure the eccentric sleeve in various adjusted positions on its bar.

4. A grinding machine for sharpening scalloped blades, comprising a base, a supporting column secured thereto, a sleeve adjustably mounted 65 upon the column supporting a transverse bar and rigidly united thereto, a sleeve slidably mounted upon the bar and rotatable thereon, a shaft mounted parallel with and carried by the sleeve and spaced therefrom adapted to swing through 70 a limited arc of travel corresponding to the arc of the blade scallops, a small diameter elongated cylindrical grinding head mounted on a forwardly extending end of said shaft, means to secure a slicing blade with its scallops in successive juxtaposition to the grinding head, and contacting lightly therewith, and 75 means to secure the eccentric sleeve in various adjusted positions on its bar.

position to the grinding head, and contacting lightly therewith.

5. In a grinding machine for sharpening scalloped bread slicing blades, the combination with 5
a suitable support, of rotatable grinding means carried by said support and pivotally united thereto to swing in a predetermined arc therefrom, corresponding to the arc of the beveled portion of the scallops in the blades to be ground, 10
means for securing said grinder in a succession of spaced positions corresponding to the scallops of the blades to be ground, means for rigidly securing the blade to be ground in a straight line and in position with a beveled face of a given 15
scallop in the arc of travel of the periphery of said grinding means and in light contact therewith, and means for driving such grinding means both rotationally and longitudinally while being swung through the above described arc. 20
6. A grinding machine for sharpening scalloped blades, comprising a base, a supporting column secured thereto, a sleeve adjustably mounted upon the column supporting a transverse shaft and rigidly united thereto, a sleeve slidably mounted upon the shaft and rotatable thereon, a shaft housing parallel with and carried by the sleeve and spaced therefrom, a grinder shaft revolvably mounted in the housing and carrying a cylindrical grinding head mounted thereon extending forwardly from the housing, in combination with a spacing head and blade holder comprising a pair of clamping plates with means for securing them to the rear edge of a blade to be ground, arms united to the opposite ends of one of said plates, a spacing head united to the arms parallel to the clamping plates, and spacing means formed in said spacing head adapted to register with the scallops of a scalloped blade secured in said clamping means, and secure such blade in position to be acted upon by said grinding head. 25
